UNITED STATES PATENT OFFICE.

CHARLES E. DAVIS, OF NORTH PLAINS, OREGON.

ELEVATED CARRIER.

1,261,717.

Specification of Letters Patent. Patented Apr. 2, 1918.

Application filed May 13, 1916. Serial No. 97,423.

To all whom it may concern:

Be it known that I, CHARLES E. DAVIS, a citizen of the United States, residing at North Plains, in the county of Washington and State of Oregon, have invented new and useful Improvements in Elevated Carriers, of which the following is a specification.

This invention relates to improvements in elevated carriers such as are employed for conveying material from one point to another and wherein the box or trough in which the material is contained is automatically dumped when the carrier reaches its destination and the carrier thereupon re-15 turned to the starting point.

The invention relates more particularly to an improved trip mechanism for such a carrier and its principal object is to provide a simple and inexpensive trip which will be 20 certain and reliable in its operation and which may be readily applied to carriers of various constructions.

An embodiment of the invention is illustrated in the accompanying drawings, 25 wherein:—

Figure 1 is a side elevation of an elevated carrier equipped with a trip in which the features of the invention are incorporated;

Fig. 2 is a detail perspective view of the 30 improved trip.

Similar characters of reference designate corresponding parts throughout the several views.

The invention is not particularly concerned with the detail construction of the carrier except in so far as it involves an invertible receptacle and a latch element for normally holding the receptacle in an upright position. The carrier is, therefore, 40 shown merely diagrammatically in the accompanying drawings and may be of any suitable construction. The carrier herein shown has a supporting frame 1 provided at its ends with depending hangers 2 which 45 have bearings for the trunnions 3 of the trough-like receptacle 4 in which the material to be transported is contained. The upper bar of the frame 1 is provided with upright standards 5 which carry pulleys 6 50 operating, as usual, on an overhead track 7.

The receptacle 4 is normally sustained in an upright position by a suitable latch which, as shown, consists of a lever 8 pivoted on a sleeve 9 adjustably mounted on one of 55 the hangers 2. The inner end of the lever 8

engages in a notch 10 formed in the upper edge of one of the end walls of the carrier or of a fixed part 11 secured to the said end wall. The lever 8 is provided beyond its pivot with an upwardly curved projecting portion 12 terminating in a lateral arm 13; and said lever is held in an operative position by a spring 14 which extends between the curved projecting portion 12 and the sleeve 9. 60

The trip mechanism consists of a vertical arm 15 which is rigidly combined with the lever 8 and a lever 16 which acts on the upper end of the arm 15 to operate the same and the lever 8. The lever 16 is pivoted between its ends to a bracket 17 secured to one of the standards 5 and projecting outwardly therefrom under and parallel to the rail 7. The lever 16 has its lower end formed as at 16^a to engage and operate the arm 15 and its upper end formed as at 16^b for engagement with and operation by a trip block 18 secured to the rail 7 at the point at which it is desired to effect the dumping of the receptacle 4. The arm 15 in the embodiment disclosed consists of a pair of bars which are secured against one another, i. e. face to face, by bolt-and-nut fastenings and which have their lower ends formed to provide a clamp 19 between whose jaws the arm 13 projects 80 and by means of which the arm 15 is rigidly held upon the said arm 13. In this way, the arm 15 forms, in effect, a rigid upward continuation of the lever 8. 85

The operation will be readily apparent 90 from the foregoing description. Assuming that the receptacle 4 is latched by the lever 8 in an upright position, when, in the movement of the carrier, the lever 16 engages with its end 16^b the block 18, the lower end 95 16^a of said lever will be thrown outward, and will thereupon effect an outward movement of the upper end of the arm 15. Since the lever 8 will move as one with the arm 15, the operation of said arm by the lever 16 100 will disengage the lever 8 from the notch 10, at which time, the receptacle 4 will be free to over-turn. The lever 16 is free to swing in either direction and on the return of the carrier will ride idly over the block 18. The 105 spring 14 will be of sufficient strength to restore the lever 8 and therewith the arm 15 to their normal positions, the arm 15 at such time bearing with its upper end against the end of the bracket 17 or the end 16^a of the 110

lever 16 in case the sleeve 9 is set at a position on the hanger 2 lower than the position shown.

The trip constructed as described constitutes an adjunct which is separable from the carrier and which may be combined with carriers of various constructions and is, therefore, readily applicable to carriers after they have been installed.

10 I claim—

The combination with an overhead rail, a block thereon, and a carrier comprising a wheeled frame movable on said rail, and an invertible receptacle carried by said frame, of a latch element at one end of said frame normally engaging said receptacle to hold the same upright, said latch element being pivoted between its ends for movement in a longitudinal plane and its engaging end being upwardly movable to release said re-

ceptacle, an arm upright from said latch element and movable as one therewith in a longitudinal plane, a lever also movable in a longitudinal plane, and a bracket to which said lever is pivoted between its ends and which supports said lever from and beyond said frame at an elevation whereby the upper end of said lever will engage said block and the lower end of said lever will simultaneously engage the free upper end of said arm and effect an outward movement thereof in connection with the operation of said lever by said block.

In testimony whereof I have hereunto set my hand in presence of two subscribing witnesses.

CHARLES E. DAVIS.
